UNITED STATES PATENT OFFICE.

WIRT S. QUIGLEY, OF NEW YORK, N. Y., ASSIGNOR TO QUIGLEY FURNACE AND FOUNDRY CO., A CORPORATION OF MASSACHUSETTS.

ADJUSTABLE AIR-BLAST APPARATUS.

1,191,226.

Specification of Letters Patent.

Patented July 18, 1916.

Application filed June 12, 1914. Serial No. 844,831.

To all whom it may concern:

Be it known that I, WIRT S. QUIGLEY, a citizen of the United States of America, residing at New York city, borough of Manhattan, county and State of New York, have invented certain new and useful Improvements in Adjustable Air-Blast Apparatus, of which the following is a specification.

My invention relates to means for adjusting the volume of delivery of an air blast while retaining constant velocity of discharge, and to the combination thereof with apparatus for feeding finely divided fuel to furnaces. In the embodiment of my invention herein shown it is applied to the type of apparatus, or controller, for feeding powdered coal to furnaces which is described in U. S. Letters Patent No. 784,307, granted J. V. Culliney, March 7, 1905, but it is, of course, capable of use with many different types of apparatus.

With the construction shown in the Culliney patent as employed to handle pulverized fuel, the finely powdered coal in surplus quantity is dropped through an air conduit chamber having transversely alined air inlet and outlet conduits. A current of air driven through these conduits carries out with it, and to the combustion chamber, the desired portion of the pulverized fuel constantly falling through the conduit. The amount of fuel dropped through the air conduit per unit of time may be varied for economy's sake, so as to avoid handling an unnecessarily large surplus but a rate of fuel flow into the air conduit in excess of the required rate of feed to the combustion chamber is always maintained, and the real control of the quantity of fuel fed to the combustion chamber is secured through varying the compressed air supply to the transversely arranged air inlet conduit. This air supply is furnished by a constant pressure blower, but if the supply to the air conduit chamber is controlled by a valve in the connections, or other ordinary regulating means, the cross sectional area of the rest of the air inlet conduit remaining constant, difficulty is encountered when the supply of air is cut down below a certain limit. The reduction in volume of air passing through the air conduit chamber in a given time produces a corresponding reduction in velocity of the stream and consequently in its power of carrying the solid particles of fuel, and

some of these are deposited in the outlet conduit, soon clogging it up. My invention overcomes this difficulty by maintaining the velocity of the air jet constant, the quantity being varied by varying the area of cross section of the nozzle of the air inlet conduit, located at or very near the wall of the air conduit chamber. This control of quantity of flow by varying the nozzle area maintains a uniform velocity of issuing jet, and uniform effectiveness of jet in maintaining the pulverized fuel in motion throughout the outlet conduit, the quantity of fuel injected into the outlet conduit varying, however, with the cross sectional area of the jet.

The best form of apparatus embodying my invention at present known to me is shown, together with certain modifications, in the accompanying three sheets of drawing, in which—

Figure 1 is a side elevation and partial section of a controller to which my invention is to be applied; Fig. 2 is a cross section taken on line 2—2 of Fig. 1; Fig. 3 is a detail view of the nozzle retaining plate and shutter; Fig. 4 is an axial cross section of the same; Fig. 5 is an end elevation partly in section of the entire apparatus, showing a modified form of shutter, and Fig. 6 is a detail side view of this modified shutter disk.

Throughout the drawings like reference characters indicate like parts.

1, represents the controller generally, which in construction conforms quite closely to that illustrated in Patent No. 784,307, above referred to, having a hopper 6, in which the pulverized fuel is placed, the horizontal conveyer screw 7, which carries a regulated portion of said fuel along to the upper end of the vertically arranged fuel conduit chamber 8, and down through which it drops, the surplus being returned by the return screw 9, to be fed over again to the fuel conduit chamber. On either side of the vertically arranged fuel conduit chamber 8, are the air conduits 2, and 4, these being alined horizontally and at right angles to the fuel conduit chamber.

2, is the outlet air discharge conduit leading to the air flue 3, and the combustion chamber (not shown) and 4, is the inlet conduit which receives a supply of air at constant pressure from an ordinary centrifugal blower 5.

The conveyer screws 7, and 9, are con-

5 nected by gearing 10, so as to rotate simultaneously, and the screw 7, is driven by an electric motor 11, through any suitable train of gearing 12. By varying the speed of the 10 motor or the relative diameters of the gears in the train 12, the speed of the conveyer screws can be varied.

15 The foregoing describes the present construction of controller mechanism for feeding 10 finely divided fuel as manufactured under Patent No. 784,307, except that some means such as a gate or a valve in the inlet conduit 4, located at some distance from the controller is employed to regulate the quantity 15 of compressed air supplied.

20 In operation the driving mechanism for the conveyer screws is arranged to drive them at a speed somewhat in excess of that necessary to deliver the maximum quantity 25 of fuel required and further regulation is secured by reducing or increasing the supply of compressed air to the inlet conduit. When the supply of air is kept down, however, the velocity of discharge into the fuel 30 conduit chamber 8, is correspondingly reduced, and while the quantity of pulverized fuel driven in to the outlet conduit 2, is properly regulated, the speed of movement therein is reduced so that a proportion of this fuel deposits in the conduit and chokes up the apparatus.

35 In my improved apparatus, I substitute for the distant valve or gate above described for controlling the supply of compressed air, means for varying the area of the opening of the discharge end of the inlet conduit at or very near to the wall of the air conduit chamber. Preferably, I employ the well known form of shutter known as the 40 Iris shutter, such as is used in photographic cameras, formed of curved wings 13, 13. Preferably the end of the inlet conduit is reduced somewhat to form a nozzle 14, which is held in an opening in the wall of 45 fuel conduit chamber 8, by means of a flange 15, perforated to permit the passage of bolts 21, 21, which also pass through the wall and through an inner retaining plate 20. Loosely threaded on this nozzle is the cap 39. Between 50 the end of the nozzle 14, and the flange 40, of cap 39, are loosely held the adjusting ring 16, and the curved wings 13, 13, surrounding the central shutter opening 44. The loosely mounted cap 39, has a lug 17, which projects rearwardly through an arc shaped slot 22, in flange 15, and terminates in a handle 18. The adjusting ring 16, has a series of radial slots 41, 41, equal in number to the number of shutter wings 13, 13. 60 Each wing 13, has at one end a rearwardly projecting pin 42, which is journaled in a hole in the face of the nozzle 14, and at the other end an outwardly projecting pin 19, which engages one of the radial slots 41, in adjusting ring 16. The cap flange 40,

has a rearwardly projecting pin 43, which engages one of said slots 41. The result of this construction is that when the handle 18, is moved so as to rotate cap 39, clockwise (looking at Fig. 3) the pin 43, causes 70 adjusting ring 16, to rotate with the cap, and, the pins 42, 42, holding one end of each curved shutter wing 13, on a fixed pivot, the pins 19, 19, on their other ends engaging slots 41, 41, of ring 16, cause the wings 75 13, 13, to move toward the center of the nozzle, thus reducing the size of the shutter opening 44. Rotation of the parts in a counter clockwise direction moves the curved wings 13, 13, away from the center and enlarges said shutter opening 14. Each movement, therefore, opens or closes the shutter 13, the opening formed, however, being always a circular one, concentric with the circular cross section of the nozzle 14. 85

90 A modified construction is shown in Figs. 5 and 6, in which I employ a rotating disk shutter 32, having openings 33, 33, of different diameter. This shutter is mounted on a pivot pin 34, in front of the end of the air inlet conduit 4, in a recess 31, in the inner face of the wall of fuel conduit chamber 8. This pin is fastened to the disk 32, as by upsetting its inner end as indicated at 35, and provided with a polygonal head 36, 95 having as many facets as there are holes 33, 33. In the construction shown in Fig. 6, the disk shutter 32, is made thin. If preferred, this shutter may be made of a thicker casting as indicated in Fig. 5, the openings 100 being partly tapered as at 37, so as to produce a tapering nozzle effect. With this construction the nozzle opening is varied by rotating disk 32, by means of a spanner applied to pivot pin head 36. The best results 105 are obtained by having the nozzle of the inlet conduit 4, of a maximum cross section of opening less than that of the outlet conduit 2, as shown in the drawings.

110 The chamber 8, may be regarded as a vertical fuel conduit, having air inlet and discharge conduits 4, and 2, opening through opposite side walls, or it may be regarded as an enlargement of the air conduit leading from blower to combustion chamber, across 115 which conduit enlargement the fuel is allowed to fall by the action of gravitation.

120 In operating my invention the blower 5, is run at constant speed and furnishes a supply of air at constant pressure independently of the quantity so delivered. By manipulating the Iris shutter 13, by means of the handle 18, the area of the opening may be adjusted to any diameter and as the pressure of air is constant the quantity of air passing through will vary directly as the area of the shutter opening. This will produce a jet of air of constant velocity but varying cross section, passing through the 125 fuel conduit chamber 8, into the outlet con- 130

duit 2. The quantity of fuel picked up by this jet and carried into and through the outlet conduit 2, will vary as its cross section but, the speed of the current being constant, there is no tendency, after this speed is properly adjusted by regulating the speed of the blower, for the fuel to deposit in the outlet conduit. I find the carrying action of the jet to be substantially uniform so far as maintaining the fuel in motion is concerned, whatever its cross section, within quite wide limits of variation of said cross section, though the quantity of fuel picked up and carried varies proportionately with the cross section of the jet.

To insure the above described operation and result, the conveyer screw 7, is continuously run at a speed which will deliver a surplus of finely divided material to the fuel conduit chamber 8, *i. e.*, more than enough to saturate the maximum air current produced when the Iris shutter is opened to its widest degree. In the modified constructions the same effect is produced by rotating the disk shutter 32, so that a larger or smaller opening comes opposite the end of the air inlet conduit. Other means for producing the above described variations of nozzle opening could doubtless be supplied by the exercise of ordinary mechanical skill.

In all cases the maximum area of opening of the inlet air conduit should be less than the fixed area of opening of the air outlet conduit.

While I have shown my invention applied to apparatus for feeding pulverized fuel, the principle involved could obviously be applied to the production of jets of fluid at constant velocity but of variable cross section when used for other purposes.

Having described my invention, I claim:

1. In an apparatus for feeding finely divided fuel the combination with a substantially horizontally disposed air conduit having an enlargement forming a chamber, and means for dropping a stream of finely divided fuel vertically through said chamber substantially at right angles to the axis of the air conduit, of a nozzle for the inlet side

of the conduit enlargement, a source of compressed air at constant pressure connected to the inlet conduit, means for varying the area of opening of the nozzle, and independent means for removing any of the material which drops below the level of the nozzle. 50 55

2. In an apparatus for feeding finely divided fuel the combination with a substantially horizontally disposed air conduit having an enlargement forming a chamber, and means for dropping a stream of finely divided fuel vertically through said chamber substantially at right angles to the axis of the air conduit, of a nozzle for the inlet side of the conduit enlargement, a source of compressed air at constant pressure connected to the inlet conduit, an Iris shutter located in the extreme outer end of said nozzle, and independent means for removing any material which may fall below the level of said nozzle. 60 65 70

3. In an apparatus for feeding finely divided material by means of an air blast the combination of a vertically arranged fuel conduit, means for dropping a stream of the material down through said conduit, oppositely disposed air inlet and discharge conduits opening through the side walls of the conduit, and means for varying the area of the inlet opening together with independent means for removing any of the material which falls below the level of the air inlet and discharge openings. 75 80

4. In an apparatus for feeding finely divided material by means of an air blast the combination of a vertically arranged fuel conduit, means for dropping a stream of the material down through said conduit, oppositely disposed air inlet and discharge conduits opening through the side walls of the conduit, and an Iris shutter located at said inlet opening together with independent means for removing any of the material which falls below the level of the air inlet and discharge openings. 85 90
